LAVATORY

William H. Armstrong, Bloomfield Hills, Mich., assignor
to Borg-Warner Corporation, Chicago, Ill., a corpora-
tion of Delaware

Filed Dec. 6, 1967, Ser. No. 9,659

Term of patent 14 years

(Cl. D23—58)

FIG.1

FIG.5

FIG.2

FIG.6

FIG.3

FIG.4

FIG. 1 is a top plan view of a lavatory showing my new design;

FIG. 2 is a sectional view of the lavatory taken along line 2—2 of FIG. 1;

FIG. 3 is a partial sectional view of the lavatory taken along line 3—3 of FIG. 1;

FIG. 4 is a partial sectional view of the lavatory taken along line 4—4 of FIG. 1;

FIG. 5 is a partial sectional view of the lavatory taken along line 5—5 of FIG. 1; and

FIG. 6 is a partial sectional view of the lavatory taken along line 6—6 of FIG. 1.

The dominant features of my design reside in the portions shown in full lines.

I claim.

The ornamental design for a lavatory, substantially as shown and described.
